(57) **CLAIM**

The ornamental design for a vehicle hood molding, as shown and described.

DESCRIPTION

FIG. 1 is a front and left side perspective view of a vehicle hood molding showing our new design;

FIG. 2 is a front elevation view of the vehicle hood molding of FIG. 1;

FIG. 3 is a left side elevation view thereof;

FIG. 4 is a right side elevation view thereof;

FIG. 5 is a back elevation view thereof;

FIG. 6 is a top plan view thereof; and,

FIG. 7 is a bottom plan view thereof.

The broken lines in the drawings depict portions of the vehicle hood molding that form no part of the claimed design.
